RAILWAY CAR CONSTRUCTION

Alfred G. Bancroft, Chicago, Ill., assignor to
Standard Railway Equipment Manufacturing
Company, Chicago, Ill., a corporation of Dela-
ware

Application April 24, 1942, Serial No. 440,279

12 Claims. (Cl. 105—410)

This invention relates to railway cars and particularly to end walls of cars adapted to haul bulk commodities, such as gondola cars and hopper cars. The walls of such cars are made of single thickness material and consequently have no lining to assist in retaining the lading.

A common type of railway car end wall is comprised of a metallic plate formed with substantially horizontal corrugations which terminate adjacent the corner posts of the car. Many new type cars embody an improved end wall wherein the vertical margins of the end wall plate are flanged on a relatively large radius and the corrugations extend at least partially around the flanges to strengthen the corner posts. Such a construction is disclosed in the patent to Jumper, et al. No. 2,185,168 of December 26, 1939. A large number of box cars have been built with end walls substantially as shown in this patent and have given satisfactory service.

The above mentioned open top cars, such as gondola cars and hopper cars, are not provided with lining and the lading is retained by the outer metallic sheathing. The provision of corrugations in the end walls creates openings between the outwardly projecting corrugations and the corner posts which permit the lading to escape into the hollow post and out the bottom of such post.

An object of the invention is to provide an end wall which embodies the advantages of the above mentioned round corner construction and which also embodies means to prevent the escape of lading from the car.

Another object is to provide means for preventing the escape of lading as herein above described without decreasing the strength of the end wall.

Other objects and advantages of my invention will be apparent from the following detailed description by referring to the accompanying drawings.

In the drawings:

Fig. 1 is an end elevation of a railway car showing one embodiment of my invention.

Fig. 2 is a partial side elevation of the car shown in Fig. 1.

Fig. 3 is a section on line 3—3 of Fig. 1.

Fig. 4 is a view similar to Fig. 1 showing a modified form of my invention.

Fig. 5 is a section on line 5—5 of Fig. 4.

Fig. 6 is a section on line 6—6 of Fig. 4.

Fig. 7 is a fragmentary view showing a modified corner construction.

Fig. 8 is a partial end elevation of another modified form of my invention.

Fig. 9 is a section on line 9—9 of Fig. 8.

The drawings show the usual parts of a railway gondola car including center sill 2; striking casting 3; side sills 5; end sill 6; side chords 8; end chord 9 and side sheathing 11. The corner post members 12 extend between and are secured to the sills and chords and the wood floor 14 is supported by the inwardly extending legs 15 of the side sills 5.

A corner post member 12 is formed with angularly disposed arms 20—21 arranged respectively normal to the side and end walls of the car and 15 the arms 20—21 are preferably provided with flanges 23—24, the flange 24 including a flat surface. The end wall plate 26 is formed with large radius flanges 27 on its vertical margins, the plate flanges 27 being secured to the flanges 23 20 of the corner post members and the body part of the end wall plate 26 being secured to the flanges 24 of the corner post members 12 to form hollow corner posts 29.

The end wall plate 26 is formed with a plurality 25 of inwardly (30) and outwardly (31) projecting substantially horizontal main corrugations which terminate and merge into the flat portion 32 of the end wall plate 26 which portion is secured to the flange 24 of the corner post member 12 in engagement with the flat surface thereof. The curved parts of the end wall plate flanges 27 are formed with a plurality of auxiliary corrugations 33 which extend around the corners and merge into the portion 32 of the end wall plate 30 26 which are secured to the corner post member flanges 24. The ends of the main (30—31) and auxiliary (33) corrugations overlap so as to transmit loads from the end wall plate 26 to the corner posts 29 and so as to cause the corrugations 30—31 40 to function as partially restrained beams. The portions 32 of the plate 26 into which the main (30—31) and auxiliary (33) corrugations merge are uninterruptedly engaged with the flanges 24 of the corner post members 12 to prevent escape 45 of lading from the interior of the car.

Fig. 7 shows a modified construction in which the flange 37 of the corner post member 38 is relatively wide in order to provide greater overlap between the main (30—31) and auxiliary (33) corrugations and thereby strengthen the connection between the end wall and the corner post.

In the modification shown in Figs. 4 to 6, the corner post members 12 are similar to those described with reference to Figs. 1 to 3. The end

wall plate 40 is formed with a plurality of inwardly (41) and outwardly (42) projecting substantially horizontal corrugations which terminate and merge into uncorrugated marginal portions 43 which are secured to the flanges 24 of the corner post members 12. Such marginal portions 43, therefore, have uninterrupted engagement with the flanges 24 of the corner post members, thereby preventing escape of lading from the interior of the car.

Auxiliary plates 44 formed on curves of relatively large radius are secured to the corner post members 12 so as to form hollow corner posts 46 and have portions 47 which overlap and are secured to the end wall plate 40. The auxiliary plates 44 are formed with a plurality of corrugations 49 which extend around the corner of the car and terminate in interlocking relation with the end portions 50 of the corrugations 41-42 in the end wall plate 40. The corrugations 41 are thus effectively extended around the corner of the car with the result that thrusts upon the end wall are more completely transferred to the corner posts 46 and the corrugations are caused to function as at least partially restrained beams.

Figs. 8 and 9 show a modified construction in which the corrugations 55 in the auxiliary plate 56 nest with and are secured to the outwardly projecting corrugations 58 in the end wall plate 59 to more effectively secure the ends of the corrugations to the corner posts 61 and to cause the corrugations 58 to function as at least partially restrained beams. The corrugations 58 terminate and merge into an uncorrugated portion 62 of the end wall plate 59 which is uninterruptedly engaged with and secured to the flange 24 of the corner post member 12 to prevent escape of lading from the interior of the car.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. For use in a railway car having a corner post member; an end wall plate having a marginal portion adapted to be secured to said member along spaced apart lines and arranged to form a hollow corner post, the said line which is most adjacent to the body part of the plate being embodied in an area of the plate which is in flatwise engagement with a part of said member to prevent escape of lading therebetween, the body part of said plate being formed with a plurality of substantially horizontal corrugations which merge into said area of the plate, said marginal portion of the plate being formed with a plurality of auxiliary corrugations which merge into said area of the plate.

2. For use in a railway car having a corner post member; an end wall plate having a marginal portion adapted to be secured to said member along spaced apart lines and arranged to form a hollow corner post, the said line which is most adjacent to the body part of the plate being embodied in an area of the plate which is in flatwise engagement with a part of said member to prevent escape of lading therebetween, the body part of said plate being formed with a plurality of substantially horizontal corrugations which merge into said area of the plate, said marginal portion of the plate being formed with a plu-

rality of auxiliary corrugations which merge into said area of the plate in overlapping relation with said first mentioned corrugations.

3. For use in a railway car having a corner post member; an end wall plate having a marginal portion adapted to be secured to said member along spaced apart lines and arranged to form a hollow corner post, the body part of said plate being formed with a plurality of substantially horizontal corrugations which merge into the plate, said marginal portion of the plate being formed with a plurality of auxiliary corrugations which merge into the plate, said member and plate being uninterruptedly engaged along substantially the full lengths of said lines to prevent escape of lading from the interior of the car, said horizontal and auxiliary corrugations merging into a flat area of said plate embodying one of said lines.

4. For use in a railway car having a corner post member; an end wall plate having a marginal portion adapted to be secured to said member along spaced apart lines and arranged to form a hollow corner post, the body part of said plate being formed with a plurality of substantially horizontal corrugations which merge into the plate, said marginal portion of the plate being formed with a plurality of auxiliary corrugations which merge into the plate in overlapping relation with said first mentioned corrugations, said member and plate being uninterruptedly engaged along substantially the full lengths of said lines to prevent escape of lading from the interior of the car, said horizontal and auxiliary corrugations merging into a flat area of said plate embodying one of said lines.

5. For use in a railway car having a corner post member having angularly disposed arms normal respectively to the side and end walls of the car, the arm normal to said end wall having a flat flange; an end wall plate having a flat portion adapted to be secured to said flat flange in flatwise engagement therewith to prevent escape of lading from the car, said end wall plate also having a marginal portion adapted to be secured to the arm which is normal to said side wall to form a hollow corner post, the body part of said plate formed with a plurality of substantially horizontal main corrugations which terminate and merge into said flat portion and said marginal portion formed with a plurality of auxiliary corrugations which merge into said flat portion in overlapping relation with said main corrugations.

6. For use in a railway car having a corner post member having angularly disposed arms normal respectively to the side and end walls of the car, the arm normal to said end wall having a flat flange; an end wall plate having a flat portion adapted to be secured to the said flat flange in flatwise engagement therewith to prevent escape of lading from the car, said end wall plate also having a curved marginal portion adapted to be secured to the arm which is normal to said side wall to form a hollow corner post, the body part of said plate formed with a plurality of substantially horizontal main corrugations which terminate and merge into said flat portion and said curved marginal portion formed with a plurality of auxiliary corrugations which merge into said flat portion in overlapping relation with said main corrugations.

7. For use in a railway car having a corner post member; an auxiliary plate adapted to be secured to said member along spaced apart lines

to form a hollow post, an end wall plate formed with a plurality of substantially horizontal corrugations which terminate adjacent a margin of the plate to form a substantially flat marginal portion therebeyond, adapted to be secured to said post, said auxiliary plate formed with a plurality of substantially horizontal corrugations which overlap the corrugations in said end wall plate, and means to secure the overlapping portions of said plates together.

8. For use in a railway car having a corner post member; an auxiliary plate formed on a curvature and adapted to be secured to said member along spaced apart lines to form a hollow post, an end wall plate formed with a plurality of substantially horizontal corrugations which terminate adjacent a margin of the plate to form a substantially flat marginal portion therebeyond, adapted to be secured to said post, said auxiliary plate formed with a plurality of substantially horizontal corrugations which extend around the curved part and overlap the corrugations in said end wall plate, and means to secure the overlapping portions of said plates together.

9. For use in a railway car having a corner post member; an auxiliary plate formed on a curvature and adapted to be secured to said member along spaced apart lines to form a hollow post, an end wall plate formed with a plurality of substantially horizontal corrugations which terminate adjacent a margin of the plate to form a substantially flat marginal portion therebeyond, adapted to be secured to said post, said auxiliary plate formed with a plurality of substantially horizontal corrugations which extend around the curved part and terminate between the end portions of the corrugations in the end wall plate, and means to secure said plates together.

10. For use in a railway car having a corner post structure comprising a vertical member comprising angularly disposed arms, one of which is

provided with a flat surface; an end wall sheet having a flat portion engageable with said flat surface substantially the width of said flat surface to prevent the escape of lading from the car, 5 said end wall sheet provided with a vertical marginal flange, a plurality of main corrugations formed with said end wall sheet, a plurality of auxiliary corrugations formed within said marginal flange, the adjacent ends of said main corrugations and auxiliary corrugations terminating in overlapping relation within said flat portion, said flat portion of the end wall sheet adapted to be secured to one of said arms in engagement with said flat surface, and the other of said 10 arms adapted to be secured to the flange of the end wall sheet to form a hollow corner post.

11. A structure as defined in claim 10 wherein the outer ends of the auxiliary corrugations merge into said flange of the end wall sheet.

12. For use in a railway car having a corner post structure comprising a vertical member comprising angularly disposed arms, each of which is provided with a flat surface; an end wall sheet having a flat portion engageable with one 20 of said flat surfaces to prevent the escape of lading therebetween, said end wall sheet provided with a marginal flange having a flat portion adapted to be secured to the other of said flat surfaces so as to prevent the escape of lading therebetween, a plurality of main corrugations formed within said end wall sheet, a plurality of auxiliary corrugations formed within said marginal flange, the adjacent ends of said main and auxiliary corrugations terminating in overlapping 25 relation within said flat portion, said end wall sheet being adapted to be secured to both of said arms, respectively, to form a hollow corner post structure.

ALFRED G. BANCROFT.
